[57] CLAIM

The ornamental design for a heat sealing iron for model airplane film covering, as shown had described.

DESCRIPTION

FIG. 1 is the front elevational view of a heat sealing iron showing my new design;

FIG. 2 is the rear elevational view thereof;

FIG. 3 is the left side elevational view thereof;

FIG. 4 is the right side elevational view thereof;

FIG. 5 is the top plan view thereof;

FIG. 6 is the bottom plan view thereof; and,

FIG. 7 is the perspective view thereof.

The electrical cord has been shown broken away to illustrate undetermined length.

FIG. 1

FIG. 3

FIG.4

FIG.2

FIG. 5
